BRAIDING CARRIER

Henry Janssen, Wyomissing, Pa., assignor to Textile Machine Works, Wyomissing, Pa., a corporation of Pennsylvania

Application November 5, 1931, Serial No. 573,143

8 Claims. (Cl. 96—15)

This invention relates to yarn carriers, and particularly to carriers employed in braiding machines; one object being to provide such a carrier with a novel yarn tensioning member for controlling bobbin engaging means adapted to permit bobbin rotation in the feeding direction as well as rotation thereof in the opposite or yarn rewinding direction, while in such engaging position.

10 The invention comprises a braiding carrier having the novel elements, features of construction and arrangement of parts in cooperative relationship as herein set forth by one illustrative embodiment thereof.

15 Other objects and attendant advantages will become more readily apparent from the following detailed description, reference being had to the accompanying drawing in which:

Fig. 1 is a side view, elevational of a braiding carrier embodying my invention; the bobbin or 20 yarn package holder being partly broken away and in section, and the yarn and yarn package being shown in dot-and-dash lines.

Fig. 2 is a fragmentary side view, similar to Fig. 1, but showing certain parts in another position.

Fig. 3 is a cross-sectional view taken substantially as indicated by the arrows 3—3 on Fig. 2.

Fig. 4 is a bottom plan view of the bobbin or 30 yarn package holder shown in Figs. 1 and 2.

Fig. 5 is a cross-sectional view taken substantially as indicated by the arrows 5—5 on Fig. 2.

Referring to the drawing, reference numeral 10 indicates a suitably shaped and constructed 35 base member or carrier which is provided with a bearing 11, and an offset portion 12.

Rigidly secured to the base member 10 is a standard 13 on which a bobbin or yarn package holder 14 is mounted for free rotation as well as 40 axial movement; the latter movement being limited by a nut 15 screwed to the upper end of standard 13. Ratchet teeth 16 are provided at the lower end of yarn package holder 14.

Fixed in the portion 12 of base member 10, is 45 a yarn guide rod 17 provided with a suitable yarn guide eyes, such as 18 and 19, through which the yarn passes, as shown in Fig. 1.

A bifurcated tension lever 20 is rockably mounted on the base member 10, which, in the present 50 instance, is made of a single piece of sheet metal and has integrally formed thereon a yarn guide hook 21 and a member 22, comprising two parts 22a and 22b. For convenience, I shall herein-after refer to the member 22 as a "cam-stop" 55 member. From Fig. 5 it will be clear that parts

22a and 22b of this member function while in ratchet teeth engaging position; the part 22a as a stop to prevent feeding rotation of the holder 14; and cam part 22b to permit the holder 14 to be reversely rotated, as for rewinding of the yarn, 60 by allowing ratchet teeth 16 to ride therealong and over stop-edge 22a. This latter action causes the holder 14 to be shifted or axially reciprocated on standard 13.

A tubular connecting piece 23, journaled in 65 bearing 11, is fixedly secured to the bifurcations of lever 20, as clearly shown, and has within it a spiral spring 24 having one end anchored to base member 10, as at 25, and its other end connected to a projecting part 26 on lever 20. The action of 70 spring 24 tends to force lever 20 downwardly and this action may be increased or decreased by simply disconnecting one of the ends of the spring and turning it one way or the other so as to increase or decrease the spring tension.

75 During normal operation, the yarn is tensioned by the lever 20 and spring 24, increasing slack being taken up when the lever moves downwardly until the yarn package stop-edge 22a of cam-stop 22 engages or contacts with a tooth 16 on 80 yarn package holder 14, and prevents further rotation of the latter. Continued feeding of the yarn then raises lever 20 until cam-stop 22 is disengaged from the tooth 16, thereby again permitting yarn package holder 14 to rotate to let 85 off yarn.

It will be noted that the cam edge 22b extends beyond the bottom edge of teeth 16 when the lever 20 is in its extreme lowered position, i. e., when the yarn is slack. Consequently, if the yarn package holder 14 is rotated in reverse direction—as 90 for instance, during reverse operation of the braiding machine in which it is employed, for the purpose of unwinding the braid and rewinding the yarn on the yarn package—teeth 16 will contact with cam part 22b, thereby forcing the yarn package holder 14 upwardly until teeth 16 pass over the stop-edge 22a. More specifically, the carrier 10 traverses a sinuous path in the slotted raceway at relatively high speed in a reverse direction, causing the carrier rapidly to oscillate about its axis; during alternate half cycles in this oscillating period the yarn carrier is intermittently rotating in a direction such that the stop-edge 22a will engage one of the teeth 16 of the 95 bobbin, as shown in Fig. 5, and the bobbin 14 will thereby be rotated in the same direction as the carrier, thus causing the yarn to be rewound on the yarn package carried thereby; during the other half cycles of the oscillating period the car- 100 110

rier 10 is intermittently rotated in a reverse direction, but due to the inertia of the yarn package and bobbin, and because of the fact that the bobbin may rise and is axially reciprocable on standard 13, the inclined surface of the cam part 22b will cause the teeth 16 of the bobbin successively to ride along the inclined surface of 22b and over stop-edge 22a, so that the bobbin does not rotate with or follow the yarn carrier 10 in its reverse rotation, but has imparted thereto an intermittent rotary motion in a direction to continue rewinding of the yarn on the package.

Of course, the braiding carrier specifically shown and described may be changed and modified in various ways without departing from the invention herein disclosed and hereinafter claimed.

I claim:

1. In a braiding carrier, the combination with a base member provided with a bearing, a bobbin standard rigidly secured to said base member, and a bobbin provided with ratchet teeth rotatably mounted on said standard; of a bifurcated yarn tension lever provided with a cam-stop member adapted to cooperatively engage said ratchet teeth to stop feeding rotation of bobbin and permit rewinding rotation thereof while in such engaging position, a tubular bifurcation connecting member journaled in said bearing, and a spring within said connecting member having one end anchored and its other end secured to said lever.

2. In a braiding carrier, the combination with a base member provided with a bearing, a bobbin standard rigidly secured to said base member, and a bobbin provided with ratchet teeth rotatably mounted on said standard and axially reciprocable thereon; of a bifurcated yarn tension lever provided with a cam-stop member adapted to cooperatively engage said ratchet teeth to stop rotation of the bobbin in one direction and permit rotation thereof in the opposite direction by axially reciprocating the same, a bifurcation connecting member journaled in said bearing, and means on said standard for limiting axial movement of the bobbin.

3. In a braiding carrier, the combination with a base member provided with a bearing, a bobbin standard rigidly secured to said base member, and a bobbin provided with ratchet teeth rotatably mounted on said standard and axially reciprocable thereon; of a bifurcated yarn tension lever provided with a cam-stop member adapted to cooperatively engage the ratchet teeth to stop rotation of the bobbin in one direction and permit rotation thereof in the opposite direction while in such engaging position, a bifurcation connecting member journaled in said bearing, and a spring for actuating the lever.

4. A braiding carrier comprising a base member, a bobbin standard secured to said base member, a bobbin rotatably mounted on said standard and axially reciprocable thereon, a ratchet element on said bobbin, a yarn tension lever fulcrumed on said base member at a point intermediate the ends of the lever, said lever having at one end thereof yarn guide means integral therewith, and having at its other end a ratchet element integral therewith adapted to coact with the ratchet element on said bobbin to stop bobbin

rotation in one direction and lift the bobbin on said standard to permit rotation of the bobbin in the opposite direction to cause rewinding of the yarn on the package carried thereby, said last named ratchet element being disposed relative to said fulcrum point so that the rewinding action of the bobbin does not affect the position of the lever at that time.

5. A braiding carrier comprising a base member, a bobbin standard secured to said base member, a yarn package bobbin rotatably mounted on said standard and axially reciprocable thereon, a ratchet member on said bobbin, a yarn tension lever fulcrumed intermediate its ends, said lever having means including a ratchet member integral therewith adapted to engage the ratchet member on said bobbin and operative during rotation of the bobbin in a direction to cause rewinding of the yarn on the package carried thereby for lifting the bobbin to permit movement of the ratchet members relative to each other, said ratchet member on the lever being disposed relative to its fulcrum point so that the rewinding action of the bobbin does not affect the position of the lever at that time.

6. A braiding carrier comprising a base adapted to travel in the raceway of a braiding machine, a bobbin standard secured to said base member, a yarn package bobbin rotatably mounted on said standard and axially reciprocable thereon, a ratchet member on said bobbin, a yarn tension lever fulcrumed intermediate its ends and having integral therewith a ratchet member adapted to coact with the ratchet member on said bobbin, one of said ratchet members having a cam surface for lifting the bobbin on its standard to permit movement of the ratchet members relative to each other during rotation of the bobbin in a direction to cause rewinding of the yarn on the package carried thereby, said cam surface being disposed relative to the fulcrum point of the lever so that the rewinding action of the bobbin does not affect the position of the lever at that time.

7. The combination with a braiding carrier, of a base member, a bobbin standard secured thereto, a bobbin rotatably mounted on said standard and axially reciprocable thereon, a thread tension control lever formed of a bifurcated member, and means integral with said bifurcated member adapted to engage said bobbin to prevent rotation thereof in one direction and to cause said bobbin to reciprocate on said standard during rotation of the bobbin in the opposite direction.

8. In a braiding carrier, the combination with a base member provided with a bearing, a bobbin standard rigidly secured to said base member, and a bobbin provided with ratchet teeth rotatably mounted on said standard and axially reciprocable thereon; of a bifurcated yarn tension lever provided with a cam-stop member extending from the end of the bifurcated part of said lever and adapted to cooperatively engage said ratchet teeth to stop rotation of the bobbin in one direction and permit rotation thereof in the opposite direction by axially reciprocating the same, and a bifurcation connecting member journaled in said bearing.

HENRY JANSSEN.
